Patented June 1, 1971

220,836

PHOTOGRAPHIC PASSENGER BUS

Fouad Said, Los Angeles, Calif., assignor to Fouad Said
Production Inc., Los Angeles, Calif.

Filed Dec. 18, 1969, Ser. No. 20,551

Term of patent 14 years

Int. Cl. D12—08

U.S. Cl. D14—3

FIG.4.

FIG.5.

FIG. 1 is a top plan view of a photographic passenger bus embodying my new design;

FIG. 2 is a rear elevational view thereof taken from the left of FIG. 1;

FIG. 3 is a front elevational view thereof taken from the right of FIG. 1;

FIG. 4 is a right side elevational view thereof, with the doors in the open position;

FIG. 5 is a left side elevational view thereof, with the doors in the open position;

FIG. 6 is a right side elevational view thereof, with the doors in the closed position; and

FIG. 7 is a left side elevational view thereof, with the doors in the closed position.

The elements shown in broken lines are included for illustrative purposes only.

I claim:

The ornamental design for a photographic passenger bus, as shown and described.
